UNITED STATES PATENT OFFICE.

OLIVER THORN, OF LONDON, ENGLAND.

DESIGN FOR A GUN-CARRYING ATTACHMENT FOR CYCLES.

SPECIFICATION forming part of Design No. 33,384, dated October 16, 1900.

Application filed August 11, 1900. Serial No. 26,656. Term of patent 7 years.

To all whom it may concern:

Be it known that I, OLIVER THORN, a subject of the Queen of Great Britain and Ireland, residing at London, England, (and whose 5 post-office address is No. 19 Great Portland street, Oxford street, London, England,) have invented and produced a new and original Design for a Gun-Carrying Attachment for Cycles, of which the following is a specification.

10 My invention relates to a new and original design for a gun-carrying attachment for cycles; and the design consists of the essential characteristics hereinafter referred to, and shown in the accompanying drawings.

15 In the accompanying drawings, Figure 1 is a side elevation. Fig. 2 is an end elevation looking in the direction of the arrow in Fig. 1, and Fig. 3 is a view looking down upon the device in Fig. 1.

20 *a* designates a continuous band of somewhat elliptical shape, one end being of slightly greater width than the other, and *b* designates a flat member or strip having a turned-up end *b'* and a turned-up end *b''* united with 25 the band *a* at opposite points in its longest dimension. The turned-up portion *b'* is somewhat longer than the turned-up portion *b''*,

and consequently the band or loop *a*, to which the portions *b'* and *b''* are connected, occupies a position or plane at a slight inclination to 30 the member *b*.

Uniting the inner face of the turned-up portion *b'* is a short curved member *e*, which extends away from the inner face of the turned-up portion *b''* and toward the flat portion *b*. 35

The essential features of the design are the elliptical continuous loop portion or band *a*, the flat member *b*, and the peculiar arrangement of the turned-up portions *b'* and *b''*, including the inclination of the portions *a* with 40 respect to the portion *b* and the location of the member *e*.

What I claim is—

The design for a gun-carrying attachment 45 for cycles substantially as herein shown and described.

In witness whereof I have hereunto set my hand in presence of two witnesses.

OLIVER THORN.
